UNITED STATES PATENT OFFICE.

EUGENE TULLAR PEARL, OF PASSAIC, NEW JERSEY.

SYRINGE.

No. 926,960.

Specification of Letters Patent.

Patented July 6, 1909.

Application filed January 2, 1909. Serial No. 470,532.

To all whom it may concern:

Be it known that I, EUGENE TULLAR PEARL, a citizen of the United States of America, residing at Passaic, in the county of Passaic and State of New Jersey, have invented new and useful Improvements in Syringes, of which the following is a specification.

My invention relates generally to fountain or gravity syringes and more particularly to means for expanding or distending the mouth of the bag to facilitate filling, etc., further to means for conveniently supporting the pipe or tubing, also the nozzle or nozzles employed in connection therewith. Syringes of this class such as are sold in drug and surgical stores generally consist of a soft rubber bag or reservoir having a small neck, tab with metal eyelet for suspending the same from a nail, the bag having a small outlet at its lower end fitted with a rubber tube to which may be attached vaginal, or enema nozzles or pipes. Fountain bags with a small neck cannot be readily filled from a pitcher or similar vessel as is often necessary, without spilling, nor can the inside of the bag be cleaned with a brush or other means as is frequently required. The nozzles after use are usually placed in the bag, this is particularly forbidden by physicians and gynecologists, and is never permitted in hospitals and sanitaria. When in use the ordinary vaginal pipe allows the medicated injections and washes to flow out over the hand while holding the nozzle in place, this is very disagreeable and annoying. The above construction is crude, unsanitary and inconvenient.

The object of my invention is to remedy these defects and provide a thoroughly sanitary and convenient syringe for family and hospital use.

The accompanying drawings will serve to illustrate a form of fountain syringe suitable for carrying my invention into effect. I wish it understood, however, that I do not limit myself to either the exact construction or arrangement of parts shown, as various changes may be made therein without departing from the spirit and scope of my invention.

In the drawings: Figure 1, is a view in elevation of the syringe showing my invention applied. Fig. 2, is a detail view of the neck portion of the bag, showing the mouth closed.

Fig. 3, is a similar view showing the mouth open and held thus distended by a ring hung within the neck of the bag. Fig. 4, is a detail view in perspective showing the ring and lug which supports it in the bag, and Fig. 5, is a similar view showing a modified form of ring.

Referring now to the drawings,—my improved syringe consists of a soft rubber bag 1, having a large neck 2, about four or five inches wide, when folded flat as in Fig. 2. Attached to the neck there is a strap 3, of sufficient length to permit the reservoir bag to be suspended from any nearby projection, bed-post or hook. Within the neck of the bag is hung an oval ring 4 of rubber covered wire (shown in Fig. 4) or of hard polished rubber (shown in Fig. 5). This ring is attached flexibly by rubber, or hinged to a lug 5 projecting from the back of the bag's neck, as shown in Figs. 1 and 3. Thus mounted, the ring may be swung downward into the bag, as indicated by dotted lines in Fig. 2, permitting the latter to be folded in a small space. When in use the ring may be drawn up firmly into the bag's neck as in Fig. 3 distending and holding the same open for easy filling from a pitcher or other vessel. Attached to the outside of the bag at the top, there are rubber elastic loops 6, for holding the several nozzles 7, when not in use. These syringe attachments are frequently misplaced or lost if kept separate from the reservoir bag.

For my improved syringe I have designed an approximately L or V shaped vaginal nozzle 8, which forms the subject matter of a co-pending application and is not therefore specifically claimed herein. As shown, this nozzle or pipe is fitted near its upper end with a valve or shut-off 9. This angular form of nozzle is not only more sanitary and convenient than the nozzles heretofore in use, for, with the shut-off placed near the discharge end or fluid exit, no air is injected, as is the case with all syringes having the shut-off on the supply pipe two or three feet from the nozzle. Again, my improved nozzle when in use, is held in position, the shut-off readily opened and closed with one hand, and the injected fluid flowing away from the parts does not come in contact with the hand, this is particularly objectionable in all other syringes, especially when medications are used. The original and peculiar

form of my angular nozzle conforms to the vaginal passage, causes no discomfort and is more sanitary and effective than any other nozzle heretofore, obtainable. The nozzle is 5 preferably made from polished hard rubber, the irrigating end being enlarged and oval shaped, the spraying exits being formed by narrow slits cut lengthwise, the extreme end not being perforated, but rounded and 10 smooth to facilitate entering and avoid clogging or choking of the outlet or outlets.

Having, therefore described my invention I claim:

1. A syringe bag provided with an open 15 inlet and means within the bag for expanding the inlet.
2. A syringe bag provided at one end with

an inlet and means within the bag movable into the inlet to enlarge the same.

3. A syringe bag open at one end and a 20 ring within the bag movable in definite relation to the open end thereof to expand the same.

4. A syringe bag provided with a flexible mouth and means within the bag shiftable 25 into the mouth to stiffen and distend the same.

In testimony whereof I affix my signature in the presence of two witnesses.

EUGENE TULLAR PEARL.
